(57) **CLAIM**

The ornamental design for a potting bench, as shown and described.

DESCRIPTION

FIG. 1 is a perspective view of a potting bench;

FIG. 2 is a top view thereof;

FIG. 3 is a front view thereof;

FIG. 4 is a back view thereof;

FIG. 5 is a right side view thereof;

FIG. 6 is a left side view thereof;

FIG. 7 is perspective view of FIG. 1 shown in an alternate position;

FIG. 8 is a top view of FIG. 7;

FIG. 9 is a front view of FIG. 7;

FIG. 10 is a back view of FIG. 7;

FIG. 11 is a right side view of FIG. 7; and,

FIG. 12 is a left side view of FIG. 7.

The broken lines shown in the drawings are included for purposes of illustrating portions of the potting bench and form no part of the claimed design. Although many broken lines and solid lines are shown in the drawings, it is contemplated by the inventors that one or more elements made be removed or added such as the front and rear supports on the lower frame section, the rear supports on the upper frame section, the first compartment, the second compartment, the lower shelf and upper shelves on the lower frame section and the shelf on the upper frame section.
